SEAMING HEAD

Stellan Birkland, San Francisco, Calif., assignor to
 American Can Company, New York, N. Y., a
 corporation of New Jersey

Application July 6, 1931, Serial No. 548,951

18 Claims. (Cl. 113—24)

The present invention relates to seaming heads such as are used in the interfolding of flanges of metallic containers and their covers and has more particular reference to a seaming mechanism adaptable for elliptical shaped cans.

The principal object of the present invention is the provision of a seaming mechanism for elliptical cans wherein the seaming elements are so controlled in their paths of travel around the can and cover being seamed as to be in proper position at all stages of the seaming cycle, thus insuring the correct following of the contour of the elliptical container and cover while bending or interfolding their flanges into the proper elliptical seam.

An important object of the invention is the provision of a seaming mechanism for elliptical cans, having seaming elements which are rotatably carried around the can and cover and are simultaneously carried through independent circular paths so that an elliptical path of travel is produced.

An important object of the invention is the provision of devices in an automatic seaming head 25 for shifting the seaming elements into proper relation to the elliptical can and cover being seamed, this shifting action compensating for the changes in shape between the periphery of the extended non-seamed flanges of the can and cover and the periphery of the finally seamed flanges.

An important object of the invention is the provision, in a seaming head, of a mechanism for effecting a rotation between the can and cover being seamed and the seaming elements while controlling in and out movement of the seaming elements relative to the central axis of the can to insure following of the periphery of the flanges of the can and cover while performing consecutively the necessary first and second operations of seaming.

A further object of the invention is the provision of an automatic seaming head adapted to rotate around a clamped and stationary elliptical container and cover, the path of travel of the seaming elements carried by the head being automatically shifted from time to time to compensate for the differences in contour of the peripheries of the flanges of the can and cover as they are altered by the seaming operations.

Numerous other objects of the invention will be apparent as it is better understood from the following description, which, taken in connection with the accompanying drawings, discloses a preferred embodiment thereof.

Referring to the drawings:

Figure 1 is a longitudinal sectional view, partly broken away of the improved seaming head and its associated actuating mechanism, a seamed can and cover being illustrated in seaming position; 60

Fig. 2 is an enlarged longitudinal sectional view through the seaming head being taken substantially along the broken line 2—2 in Fig. 3;

Fig. 3 is a plan sectional view of the seaming head taken substantially along the line 3—3 in 65 Fig. 2;

Fig. 4 is a plan, sectional view taken substantially along the line 4—4 in Fig. 2;

Fig. 5 is a fragmentary sectional view of a portion of the seaming head, as viewed along the 70 broken line 5—5 in Fig. 4;

Fig. 6 is a plan sectional detail taken substantially along the line 6—6 in Fig. 2;

Fig. 7 is an under or bottom plan view of the seaming head, as viewed from a plane indicated 75 by the broken line 7—7 in Fig. 2;

Fig. 8 is a plan sectional view, partly broken away, taken substantially along the line 8—8 in Fig. 1; and

Figs. 9, 10 and 11 are diagrammatic plan views 80 of parts of the principal seaming and chuck elements illustrating different stages of seaming, projected paths of travel of a seaming roller element being graphically shown.

The present invention is directed to an apparatus for seaming an elliptical shaped container wherein a rotating seaming head is caused to move at a relatively high speed around a container and cover which is preferably clamped between a stationary chuck and a stationary plunger or 90 can support. A pair of first operation seaming rollers and a similar pair of second operation seaming rollers are bodily carried by the rotating head. These rollers are eccentrically mounted on the lower ends of vertically disposed spindles 95 which are continually rotated by geared connection with a central gear.

This rotation of the spindles causes the seaming rollers to be moved in and out toward and away from the central axis of the chuck, the eccentricity of the mountings of the rollers on the spindles insuring inward movement of the rollers when traversing the narrow sides of the elliptical can adjacent the short axis and outward movement of the rollers when traversing the wide sides 105 adjacent the long axis thereof.

The unseamed flanges of the can and cover projects beyond the body wall of the can, the outer periphery thereof extending in a larger elliptical curve than the curve of the finished 110

seam and this makes it necessary to further coordinate or adjust the travel of the seaming rollers when engaging the extended flanges of the can and cover and as the flanges are interfolded in the seam, correction in travel is made for the diminishing size of the seamed parts. This compensating action is preferably effected by a controlled shifting of the rotation of the seaming spindles.

- 10 The combined movements of rotation of the seaming head, rotation of the seaming roller spindles and the compensating movements on the latter insure the proper travel of the seaming rollers around the clamped can and cover.
- 15 Independent in and out movements of the seaming rollers are provided for performing the first and second operations of seaming and for clearing the can and cover as they are "chucked" and discharged. Each seaming roller spindle is
- 20 mounted in a lever for this purpose and the levers are bodily shifted to bring the rollers into seaming positions.

The can after being seamed is removed from the head by a lowering of the can support, being positively ejected from the chuck by a knockout mechanism. This is followed in uninterrupted order by the replacement of a succeeding unseamed can while the can support is in its lowered position. This cycle of operations continues

30 without any cessation in rotation of the seaming head, all of the parts being so synchronized as to insure proper intercorrelation between the various operations.

The preferred form of apparatus disclosed in the drawings for the purpose of illustrating the present invention comprises a housing or frame 51 (Figs. 1, 2 and 3) having an upper gear section 52 preferably formed integrally therewith. This support housing or frame 51 may be part of a seaming machine of either the single spindle or the multiple spindle type. The housing, as illustrated in the drawings, is best adapted to the single spindle type, and is stationary. The housing 51 supports the seaming head proper

45 and encloses parts of the actuating mechanism for the lifting and positioning of the can and mechanism for the actuating of the seaming head.

The housing 51 is extended adjacent its lower end to provide a casing 53 in which bearings 54 are mounted. A vertically extending shaft 55 has sliding movement within the bearings 54 and carries a plunger or can support 56 on its upper end. It is on this support that a container 57 and its cover 58 are positioned prior to seaming.

The shaft 55 is adapted to be raised and lowered by a cam control device, a collar 61 being secured to the shaft intermediate the bearings 54 and being engaged by pins 62 carried on the forward end of a lever 63 pivoted on a stud 64 carried in a bracket 65 formed as an integral part of the casing 53. The opposite end of the lever 63 carries a cam roller 66 which operates within a cam groove 67 formed in a cam 68 keyed to a vertical shaft 69. The shaft 69 is journaled in a bearing 71 formed in the housing 51 and in bearings 72 formed in the gear housing section 52.

The shaft 69 is continually rotated, a worm gear 73 secured to the shaft being provided for this purpose. The gear 73 meshes with a worm 74 mounted on a horizontal drive shaft 75 journaled in bearings 76 formed in the gear section 52. The shaft 75 has rotating power applied thereto as through a belt pulley 77 mounted on the shaft exterior of the housing.

The seaming head is suspended from the housing 51 and comprises a lower body 81, (Figs. 1 and 2), an upper body 82 and a cover plate 83. The body sections and the cover plate are bolted together by vertically extending studs 84 threadedly engaging the lower body 81 and extending upwardly through the cover plate 83 where they are engaged by locknuts 85. The seaming head body parts 81, 82, 83 revolve around a stationary chuck 91 which is secured by screws 92 to an enlarged head 93 formed on the lower end of a vertically extending chuck spindle 94 passing upwardly through the seaming head, a ball bearing unit 90 being interposed between the chuck spindle and seaming head body 81.

The upper end of the chuck spindle 94 is threadedly engaged in a clamp bracket 95 which is mounted upon and carried by a frame 96 formed as an integral part of, and extending forwardly from, the gear housing 52. A clamping bearing frame 97 is secured by bolts to the frame 96 which is further clamped to the gear housing 52. An outer circular guard plate 99 is secured to the housing 52 and rests beneath the housing 98, this plate enclosing the front of the seaming head.

The frame 96 at its lower end is extended forwardly and rounded out as a circular boss 101 (Fig. 2) which is threaded at 102 to securely hold a clamping nut 103 and parts carried thereby. The nut 103 locks an inner ring 104 of an anti-frictional ball bearing unit 105 to the boss 101. An outer ball race 106 of the unit 105 is clamped in a seat 107 formed in a cup gear 108 which is internally threaded at 109 to provide engagement for a clamping disc 111. The gear 108 is formed with bevel gear teeth 115 which mesh with a bevel gear 116 keyed at 117 to the forward end of the shaft 75. Rotation of the shaft 75, through the gear elements 116, 115 is thus transmitted to the cup gear 108.

The gear 108 is provided with a downwardly extending body sleeve 121 which is located on and encloses the lower part of the chuck spindle 94. The sleeve 121 terminates in a threaded bottom end 122 which provides engagement for a locknut 123. This locknut supports an inner body sleeve 124 of the lower seaming head body 81, a washer 125 being interposed between the nut and the sleeve. The parts 121, 124 are also keyed together at 126. The entire seaming head and parts carried thereby are thus supported from above on the bearing unit 105 and turn with the sleeve 121 and gear 108 at a uniform speed of travel.

The seaming head carries four vertically extending pivot pins 131 (Figs. 2 and 5), each pin being held in fixed position within a boss 132, formed in the lower body 81, and within a boss 133 formed in a web 134 of the upper body 82.

A seaming lever 135 is pivotally mounted on each pin 131, these four levers being carried around with the rotating seaming head. One end of each lever is enlarged to provide a boss or sleeve section 136 in which is formed a vertical central bore 137 and two enlarged end counterbores 138, 139. The sleeve section 136 of each lever is enlarged, top and bottom, into bosses 141, 142 to provide the necessary stock surrounding the counterbores. Stationary elements 143, 144 of ball bearing units 145, 146 are located in the counterbores.

A seaming roller spindle or shaft 151 (Fig. 2) is rotatably mounted in the sleeve section 136 of each seaming lever 135, each shaft carrying movable elements 152, 153 of the respective bear-

ing units 145, 146. A bushing 154 is located in the bore 137 and is interposed between each set of bearing elements 152, 153 and assists in aligning the spindle shaft within its lever.

5 The lower end of each shaft 151 is provided with an enlarged head 161 which is positioned beneath the bearing unit 146 and the upper end of the shaft extends into a reduced threaded neck 162 which is threadedly engaged by a lock-nut 163. A gear 164 is keyed to and mounted upon the upper end of each shaft 151 and its hub rests against the bearing element 152. A washer 165 is clamped against the gear 164 being held in position by the locknut 163. This locknut securely holds the parts 153, 154, 152 and 164 as a solid unit with the shaft spindle by clamping these parts between the shaft head 161 and washer 165. This construction provides a spindle shaft which is free to turn within the enlarged end 136 of the lever 135 and one in which vertical movement is prevented.

20 The lower body 81 (Figs. 2 and 7) is cut away at 171 adjacent each of the lever ends 136 to allow clearance thereof during movement of the lever and the horizontal web 134 of the upper body 82 is similarly recessed at 173 to provide clearance for the shaft 151 and gear 164 extending above the lever end. This web 134 adjacent the recess 173 is counterbored at 174 to accommodate a washer 175 and a second washer 176 is mounted on the upper face of the lever boss 136 and partially encloses the bearing unit 145.

25 A washer 177 is also provided, being secured by a screw 178 against the bottom surface of the web 134. The washers 176, 177 have sliding movement one on the other during movement of the lever 135. A collar 181 surrounds the reduced hub of the gear 164 and is provided with a horizontal flange 182 which extends over and slides upon the upper face of the washer 175. The flange 182 of the collar 181 is slotted at 183 to accommodate a pin 184 set into the web 134. This slotted connection allows lateral sliding movement of each collar 181 as the associated 30 seaming lever 135 rocks on its pivot 131 and as its spindle shaft 151 rotates, the flange 182 maintaining a closure plate for the opening 173.

35 Two first operation rollers 193 (Figs. 2 and 7) and two second operation rollers 194 are preferably used in the seaming head. These seaming rollers are rotatably mounted upon studs 195 projecting downwardly from each spindle head 161. The two first operation rollers are arranged diametrically opposite each other and the two second operation rollers are similarly diametrically disposed but at right angles to the first operation 40 rollers.

45 Each seaming roller 193 or 194 is rotatably held on its stud 195 by means of a washer 196 held on to the lower end of the stud by a screw 197 and a washer 198 is interposed between the upper face of the roller and the lower face of the head 161. Such a mounting for each seaming roller allows it to rotate freely on its vertical stud and it is bodily moved with its seaming lever and spindle shaft.

50 Each stud 195 is eccentrically mounted relative to the center of its spindle shaft 151 by a distance equal to one-half of the difference between the long and short axes of the chuck 91. This amount of eccentricity, upon rotation of the individual shaft 151 moves its roller toward and away from the central axis of the chuck so that as the seaming head is rotated around the chuck the roller will describe an elliptic path of travel.

55 In other words, when the throw of the eccentricity of the shaft 151 moves the roller outwardly it is adjacent the end of the long diameter of the ellipse and when the throw of the eccentric moves the roller inwardly its full amount, the roller is at the end of the short axis of the ellipse. It will be understood that the two seaming rollers of each operation are opposite each other so that one roller is at the end of the long axis of the chuck, for example, when its companion roller is at the opposite end of the long axis.

60 Rotation of the shaft 151 to effect this eccentric movement of the seaming rollers is provided by a geared connection, illustrated in Figs. 2 and 3. For this purpose the upper end of each pivot pin 131 is reduced in diameter at 201 to provide a support for a composite gear 202 rotatably mounted thereon. This gear 202 rests upon a washer 203 which in turn rests upon the shoulder formed by the junction of the two diameters of the pin 131.

65 Anti-frictional bearings 204, 205 are located between the gear 202 and the pin section 201 being held in position with the gear by a stud 206 having a head 207 which rests on top of the gear 202. This allows free turning of the gear upon the pivot pin. Each gear 202 is provided with gear teeth 208 which mesh with one of its companion gears 164. The gear 202 is also provided with gear teeth 209 which mesh with a gear 211 formed on the lower end of a gear collar 212 loosely mounted on an auxiliary bushing 213 which has a supporting shoulder 214 at its bottom end. The upper end of the auxiliary bushing 213 is grooved at 215 for clamping connection with the housings 51 and 98.

70 The gear collar 212 at certain times has slight oscillatory movement around the central axis of the seaming head, as will be hereinafter explained, but otherwise it is stationary. During the stationary or rest periods of the gear collar each gear section 209 traverses the teeth 211 at a uniform speed, this being as the seaming head revolves around the chuck. Rotation of the gear 202 on its supporting pin 201, through the gear 208, produces a similar rotation of the associated gear 164. The gear 164 in turn rotates the associated seaming shaft spindle 151 and carries the seaming roller in and out for its proper 75 travel.

75 A further independent movement of the seaming rollers 193, 194 toward and away from the axis of the chuck is necessary for seaming and this is obtained by a bodily shifting of their associated seaming levers 135. Each seaming lever 135 is slotted at 225 (Figs. 2 and 4) to provide for a lever arm 226 loosely mounted on the pin 131.

80 Each arm 226 extends inside of its associated lever 135 or towards the center of the seaming head and its inner end is bifurcated at 227 to provide spaced supports for a vertically disposed pin 228. A slot 229 is thus formed in this end of the arm 226 and a cam roller 231 is located therein being loosely mounted upon the pin 228. A boss 232 (Figs. 4 and 5) is also formed in the lever arm and a hardened steel plate 233 is positioned against and fixed to the boss.

85 The end of each lever 135 opposite to its enlarged end 136 is laterally bored and threaded at 234 for the reception of an adjusting set screw 235 held in adjusted position on the lever by a lock-nut 236. The lever 135 at this end is recessed and carries a button 237 which supports one end of a clamping spring 238 interposed between the lever 150

and a boss formed in the wall of the head body 81. A second button 239 carried in the boss holds the opposite end of the spring in proper position. Each spring 238 holds the set screw 235 5 against the plate 233 on the lever arm 226, forcing the same inwardly and holding its cam roller 231 against a cam track.

The cam rollers 231 associated with the first 10 operation of seaming are in a higher plane than those associated with the second operation levers. A peripheral cam track 241 (Figs. 2, 4 and 5) is formed in the outer wall of a sleeve double cam 242 and provides the cam surface against which the first operation cam rollers engage. A second 15 cam track 243 just below the cam track 241 provide the working surfaces for the cam rollers of the second operation seaming rollers.

The double cam 242 (Figs. 4 and 5) is rotatably 20 mounted outside of and turns on the body sleeve 124, a lower tapered edge 244 of the cam engaging a conical seat 245 formed in the body sleeve. The relative difference in rotation between the double 25 cam 242 and the body sleeve 121 produces a slow rate of travel therebetween, the cam making one-half of one revolution relative to the body sleeve during the entire seaming head cycle. This cycle 30 includes not only the formation of the first and second operation seams but also the placing of the can and cover into seaming position and the removal from the head after seaming.

This relative rotation of the cam is effected by 35 means of gearing, associated with the drive shaft 75. The upper end of the cam 242 is provided with four upwardly extending tongues 251 (Figs. 35, 2, 5, and 6) which protrude into four slots 252 formed on the bottom end of a sleeve gear 253 which is rotatably disposed between the body sleeve 121 and the auxiliary bushing 213.

The sleeve gear 253 is enlarged at its upper end 40 into a horizontal shoulder 254 which bears against an upper formed end 255 of the auxiliary bushing 213 and which engages a washer 256 resting on the clamping surfaces of the frames 52, 98. A circular wall 257 projects upwardly from the shoulder part 254 and its upper edge is provided with gear teeth 258. These gear teeth 258 are located outside of and directly beneath the gear teeth 115 of the body sleeve 121 as best shown in Figs. 1 and 2.

50 The gear teeth 258 mesh with a bevel gear 261 secured by bolts 262 to the gear 116. The gears 116, 261 move together with the drive shaft 75 and severally engage and rotate the gears 115, 258 but the gear ratio between the two gear sets 55 differs which gives the necessary differential for the relative movement between the body sleeve 121 and the cam 242.

After the double seam has been completed, under the proper action of the seaming rollers just 60 described, the can and cover are ejected from the seaming head as the plunger 56 is lowered. This ejecting device comprises a knockout pad 275 (Fig. 2) carried on the lower end of a vertically disposed knockout rod 276 extending throughout 65 the length of the chuck spindle 94. The upper end of the knockout rod 276 carries a collar member 277 (Fig. 1) having a groove 278 which is engaged by inwardly projecting pins 279 carried on the forward bifurcated end of a knockout lever 70 281 pivoted at 282 on a bracket 283 supported upon a shelf 284 formed in the gear housing 52. The opposite end of the lever 281 carries a cam roller 285 which operates within a cam groove 286 of a barrel cam 287 keyed to the upper end of the shaft 69.

The knockout lever mechanism just described is housed within a casing cover 288 carried on the upper end of the gear housing 52. Rotation of the cam 287 operating against the roller 285 oscillates the lever 281 rocking it on its pivot 282 and this movement lowers the knockout rod 276 and knockout pad 275 in proper synchronism to eject the seamed can and cover from the chuck 91. During the seaming operation the knockout pad 275 (Fig. 2) rests within a pocket 291 formed in the chuck 91.

Reference should now be had to a previous statement respecting the oscillatory movement of the gear collar 212. The reason for such movement will now be explained. Without any such movement, that is with a stationary gear 211, rotation of the seaming spindles 151 is uniform as the seaming head revolves at a uniform rate of travel and the resulting elliptic path of travel of a seaming roller is of the same shape and size 95 as that of the can wall.

The seaming rollers 193, 194, however, in order to clear the extending and enlarged unflanged can and cover as they are positioned on the chuck 91, are spaced apart from the edge by shifting of 100 the seaming levers. The beginning of the seaming movement of the rollers, therefore, takes place from this greater diameter distance. To produce a uniformly tight seam the seaming roller path must be corrected or compensated and this 105 is preferably done by an oscillation of the gear collar 212. These conditions are graphically illustrated in Figs. 9, 10 and 11 and reference should be had thereto.

In moving the seaming rollers to their outermost positions, not only is the center of each roller shifted a greater distance from the center of the chuck but by reason of the necessary movement of the seaming lever 135 around the center of the pivot 131, the center of the seaming roller is moved 115 laterally of the center line of the chuck.

The long axis of the chuck 91 is indicated by the letters $a-o$, the short axis by the letters $b-o$. The outside periphery of the chuck, indicated by the letter W , is of elliptical shape to fit 120 within the channel of the can cover 58 and this is unaltered in the three views.

In Fig. 9, the outside periphery of the unseamed flange of the can cover is indicated by the letter X , this line being parallel to the outer edge of the 125 chuck periphery W . The outside diameter of the contacting seaming surface of a seaming roller 193 or 194 is indicated by the letter c and the orbit of the roller center around the center e of the spindle 151 is indicated by the letter d . The 130 center of the pivot 131 of the seaming lever is designated by the letter f .

In Fig. 9, the seaming roller seaming surface c is clear of and out of contact with the outer periphery X of the can cover 58, this being the 135 position of parts when a can and cover are clamped against the chuck 91. In this spread or outermost position of the roller its center d is removed or laterally displaced from the axis $a-o$ of the chuck.

The elliptical path of travel which would be produced by the innermost points of tangency of the seaming surface c of the roller, indicated by the letter Y , it will be observed, is not in coincidence with the chuck axis. In other words, the long axis of such an elliptic path of travel, $(m-o)$ and the short axis thereof $(n-o)$ do not coincide with the axes $a-o$, $b-o$. The resulting seam would be uneven, tight in one place and 145 150

loose in another, as would be produced by a stationary gear collar 212.

It is necessary, therefore, in order to make an even seam, to shift the axis $m-o$ and $n-o$ about the center o and bring them into coincidence with the axes $a-o$ and $b-o$. Such a shifting of the path of travel of the seaming roller is effected by an oscillation of the gear collar 212 on the vertical axis of the seaming head. As the seaming 10 proceeds and the outer periphery of the seam gets smaller and smaller other shifting or compensation is made (Fig. 11).

In actual practice the shifting of the axes $m-o$, $n-o$ is at all times so performed as to 15 keep these axes in coincidence with the axes $a-o$, $b-o$. The difference in position between the fanciful line Y and the cover periphery X never actually exists and is only illustrated and described to more clearly point out the compensating 20 operation.

The mechanism for accomplishing this compensation is perhaps best shown in Figs. 1, 2 and 8. A collar 301 is keyed at 302 to the upper end 25 of the gear collar 212 and an arm 303 projects outwardly therefrom. The arm 303 extends through an opening 304 formed in the frame 51 and its end carries a cam roller 305 which operates within a cam groove 306 formed in a face cam 307 keyed to the shaft 69 directly beneath 30 the lower bearing 72.

Rotation of the cam 307 throughout certain 35 periods, slightly oscillates the arm 303 and the collar 301 causing a corresponding shifting of the gear 211. Such a shifting movement transmitted through the composite gear 202 varies the uniform rotation of the roller shafts 151 as just described. The seaming rollers 193, 194 carried thereby are thus caused to move in the proper 40 corrected path of travel or into coincidence at all times with the periphery of the flange of the can cover being seamed.

It will be observed that the mechanism just described controls the position of the seaming rollers throughout all stages of the seaming operation 45 so that their paths of travel will properly follow the periphery of the flange of the can cover regardless of the stage of seaming and the exact shape of the partially completed can cover seam. Furthermore, the principal movements in the 50 seaming head are rotary and, therefore, adapted to high speed.

It is thought that the invention and many of its attendant advantages will be understood from the foregoing description and it will be apparent 55 that various changes may be made in the form, construction and arrangement of the parts without departing from the spirit or scope of the invention or sacrificing all of its material advantages, the form hereinbefore described being 60 merely a preferred embodiment thereof.

I claim:

1. In a seaming head for elliptical seaming, the 65 combination of a stationary elliptical chuck for holding an elliptical can and cover to be seamed, a seaming head body having rotative movement around said chuck and can and cover held thereby, seaming rollers carried by said body, an oscillatory gear and connections for moving said 70 seaming rollers toward and away from the central axis of said chuck during rotation of said head to cause said rollers to describe an elliptical path of travel, and means for shifting said rollers into seaming and non-seaming position.

2. In a seaming head for elliptical seaming, the 75 combination of a stationary elliptical chuck, a

support plunger positioned in axial alignment and adapted to cooperate with said chuck for holding an elliptical can and cover to be seamed, a seaming head body having rotative movement around said chuck and can and cover held thereby, seaming rollers carried by said body, a central gear and connections for moving said seaming rollers toward and away from the central axis of said chuck during rotation of said head to cause said rollers to describe an elliptical path of travel, and means for shifting said rollers into seaming and non-seaming position.

3. In a seaming head for elliptical seaming, the combination of an elliptical chuck for holding a can and cover to be seamed, a seaming head body having rotative movement relative to said chuck, seaming rollers carried by said body, eccentric means and a central toothed gear for moving said seaming rollers in and out during the relative movement between said chuck and body to cause said rollers to describe an elliptical path of travel, said eccentric means causing the said roller path of travel to be parallel with the peripheral seam parts of the can and cover, and means for moving said seaming rollers into and out of seaming position.

4. In a seaming head for elliptical seaming, the combination of an elliptical chuck for holding a can and cover to be seamed, a seaming head body having rotative movement relative to said chuck, seaming rollers carried by said body, eccentric rotary means and a central toothed gear for moving said seaming rollers toward and away from the central axis of said chuck during the relative movement between it and said body to cause said rollers to describe an elliptical path of travel, said eccentric means acting on said rotary means to cause said roller path of travel to be parallel with the elliptical contour of the can, and other means acting on said rollers for moving them into seaming and non-seaming position.

5. In a seaming head for elliptical shapes, the combination of a stationary elliptical chuck for holding a can and cover to be seamed, a seaming head body having rotative movement around said chuck, seaming rollers carried by said body, eccentric rotary means and a central toothed gear for moving said seaming rollers toward and away from the central axis of said chuck while being carried around with said body to cause said rollers to describe an elliptical path of travel and for causing said roller path of travel to be parallel with the periphery of the can and cover flanges being seamed, and other means for moving said seaming rollers into and out of seaming position.

6. In a seaming head for elliptical shapes, the combination of a stationary elliptical chuck, a support plunger positioned in axial alignment and adapted to cooperate with said chuck for holding a can and cover to be seamed, a seaming head body having rotative movement around said chuck, seaming rollers carried by said body, rotary means and a central toothed gear for moving said seaming rollers toward and away from the central axis of said chuck while being carried around with said body to cause said rollers to describe an elliptical path of travel and for causing said roller path of travel to be parallel with the periphery of the can and cover flanges being seamed, and other means for moving said seaming rollers into and out of seaming position.

7. In a seaming head for elliptical shapes, the combination of a stationary elliptical chuck for

- holding a can and cover to be seamed, a seaming head body having rotative movement around said chuck, seaming levers carried by said body, roller spindles rotatively mounted in said levers, rollers 5 eccentrically mounted on said spindles, means for rotating said spindles while being carried around said chuck by said head to cause said rollers to describe an elliptical path of travel, means for altering the rotative movement of said 10 spindles to cause their elliptical paths to be parallel with the periphery of the can and cover flanges being seamed, and means for oscillating said levers relative to said body for moving said seaming rollers into and out of seaming position.
- 15 8. In a seaming head for elliptical shapes, the combination of a stationary elliptical chuck for holding a can and cover to be seamed, a seaming head body having rotative movement around said chuck, a plurality of seaming levers carried by 20 said body, first operation rollers carried by certain of said levers and second operation rollers carried by the other of said levers, rotary gearing for moving said rollers relative to and on said levers during the rotation of said head to cause 25 said rollers to describe elliptical paths of travel corresponding to the elliptical can and cover being seamed, and means for oscillating said levers to move said seaming rollers into and out of seaming position.
- 30 9. In a seaming head for elliptical shapes, the combination of a stationary elliptical chuck for holding a can and cover to be seamed, a seaming head body having rotative movement around said chuck, a plurality of seaming levers carried by 35 said body, first operation rollers carried by certain of said levers and second operation rollers carried by the other of said levers, means for moving said rollers on said levers during the rotation of said head to cause said rollers to describe 40 elliptical paths of travel corresponding to the elliptical can and cover being seamed, means also acting on said rollers for causing their paths of travel to be parallel with the elliptical flanges of the can parts being seamed, and means for 45 oscillating said levers to move said seaming rollers into and out of seaming position.
10. In a seaming head for elliptical shapes, the combination of a stationary chuck, a seaming head having relative movement around the chuck, seaming levers pivotally mounted on the head, rotary spindles carried by said levers, seaming rolls mounted on said spindles eccentrically thereto, a gear concentric with the seaming head and turnable relative thereto, gearing connecting said 55 concentric gear with said spindles, means for oscillating said concentric gear to swing the seaming rolls relative to the axes of said spindles to cause the seaming rolls to follow an elliptical path around the chuck, and means for swinging said levers to give seaming operation to said rolls.
- 60 11. In a seaming head for elliptical seaming, the combination of a stationary elliptical chuck, a support plunger positioned in axial alignment and adapted to cooperate with said chuck for holding an elliptical can and cover to be seamed, a seaming head body having rotative movement around said chuck and can and cover held thereby, seaming rollers carried by said body, means 65 having an eccentricity equal to one half of the difference between the short and long axes of said elliptical chuck for moving said seaming rollers toward and away from the central axis of said chuck during rotation of said head to cause said 70 rollers to describe an elliptical path of travel,
- and means for shifting said rollers into seaming and non-seaming position.
12. In a seaming head for elliptical shapes, the combination of a stationary elliptical chuck for holding a can and cover to be seamed, a seaming head body having rotative movement around the axis of said chuck, seaming levers carried by said body, seaming rollers carried by said levers and movable inwardly and outwardly and following an elliptical path around the chuck, a sleeve cam mounted on said body and having a different rate of rotation around the axis of said chuck, and lever arms interposed between said levers and said cam for imparting movement to said levers and the seaming rollers carried thereby for performing the seaming operation on the said can and cover, and a central gear and pinions for moving the seaming rolls.
- 80 13. In a head for seaming elliptical shapes, in combination, a seaming element on said head and movable relative thereto and adapted to be carried around the head in a certain path, and gearing and movable parts on said head and connecting the seaming element with an operative part of the head comprising a central toothed gear 100 held from movement with the seaming head, for changing the otherwise circular path of the seaming element and driving it in an elliptical path.
- 85 14. In a head for seaming elliptical shapes, in combination, a seaming element on said head and movable relative thereto and adapted to be carried around the head in a certain path, and toothed gearing and movable parts on said head and connecting the seaming element with a toothed operative part held from turning with the 110 head, for changing the otherwise circular path of the seaming element and driving it in an elliptical path, and means for moving said operative part of the head to correct the path of the seaming element.
- 90 15. In a seaming head for elliptical shapes, in combination, a gear on said head, a seaming element, a seaming lever carrying said element, a pivot fixed to the seaming lever, a rotary part on the seaming head and carried thereby in a circular path and located eccentric relative to said 120 pivot and carrying it in a certain path, and rotary gearing connecting said gear on the seaming head and said rotary part and said pivot of the seaming lever, to drive the seaming element away from a 125 circular path and in an elliptical path.
16. In a seaming head for elliptical shapes, in combination, a gear on said head, a seaming element, a seaming lever carrying said seaming element, a pivot fixed to the seaming lever, a rotary part on the seaming head and carried thereby in a circular path and carrying said pivot in a path circular relative to the rotary part, gearing connecting said gear and rotary part and seaming 130 lever pivot to drive the seaming element in an elliptical path, and means for oscillating said 135 gear to correct the path of the seaming element.
17. In a seaming head for elliptical seaming, the combination of an elliptical chuck for holding a can and cover to be seamed, a seaming head body having rotative movement relative to said chuck, rotary spindles revolving around with said head, seaming levers having pivots parallel with said spindles, and eccentric thereto and carried by the head, seaming rollers carried by said levers, 140 and a system of gearing for turning said spindles and pivots and moving said seaming rollers toward and away from the central axis of said chuck during the relative movement between it and said body to cause said rollers to describe an 145 150

elliptical path of travel, and means for shifting said rollers into seaming and non-seaming position.

18. In a seaming head for elliptical seaming, the combination of an elliptical chuck for holding a can and cover to be seamed, a seaming head body having rotary movement relative to said

chuck, a plurality of seaming rolls, rotary members immediately supporting the seaming rolls respectively and means for carrying said rotary members around with the seaming head body, and gearing for rotating said rotary members. 80
